C. A. MEALY

BRACELET

Filed June 20, 1924

Inventor

Charles A. Mealy
By Joseph A. Miller

Attorney

UNITED STATES PATENT OFFICE.

CHARLES A. MEALY, OF PROVIDENCE, RHODE ISLAND, ASSIGNOR TO THE HADLEY COMPANY, OF PROVIDENCE, RHODE ISLAND.

BRACELET.

Application filed June 20, 1924. Serial No. 721,367.

To all whom it may concern:

Be it known that I, CHARLES A. MEALY, a citizen of the United States, residing at Providence, in the county of Providence and State of Rhode Island, have invented new and useful Improvements in Bracelets, of which the following is a specification.

This invention relates to certain new and useful improvements in bracelets and relates 10 more particularly to bracelets of the expandable type.

The primary object of the invention is to provide a bracelet which enables the links to be easily and quickly connected and disconnected and which has novel means for connecting and tensioning the links.

The invention further aims to provide means for enabling connection and disconnection of the links, which is of simple and 20 economical construction.

The invention has still further and other objects which will be later set forth and manifested in the course of the following description.

25 In the drawings:—

Figure 1 is a fragmentary plan view with the back of the links applied thereto.

Figure 2 is a section on line 2—2 of Figure 1.

30 Figures 3, 4 and 5 are sections on lines 3—3, 4—4 and 5—5 respectively of Figure 2.

In proceeding in accordance with the present invention each link is composed of a box 1, a back 2, a slide 3 and a coil spring 35 4.

The box has a pair of spaced hook-line or L-shaped lips 5 at one end and has its opposite end slotted at 6. The slide is of substantially L-shape and has a pair of ears 7 extending outwardly from its sides at one

40 end thereof, while its opposite or right angular end 9 has a similar pair of guide ears 8 extending outwardly from its sides and at substantially right angles to the ears 7. The right angular end 9 of the slide provides an abutment for one end of the spring 4, while the back 2 has an inwardly extending end 10 that provides an abutment for the opposite end of the spring. The slide has a pin-hole 11, between its ends for a purpose now to be

45 set forth.

In assembly, the slide is placed in the box as shown in the drawings, the spring placed on the slide in abutting engagement with the end 9 of the slide, and the back is then applied with its end 10 in abutting engage-

ment with the opposite end of the spring whereupon the sides of the box are bent over the sides of the back at 1^A to hold the latter in position. The ears 7 project outwardly from an end of the completed or assembled structure and are formed for engagement with the L-shaped lips 5 whereby the adjacent links are connected and still permitted relative hinged or pivotal movement so as to provide a flexible link structure. The ears 8 guide the slide and hold same against lateral movements. The spring acts on the end 9 of the slide and thus holds the lips 5 and ears 7 engaged. In order to disconnect the parts the slide is pulled outwardly and a pin P inserted through the pin hole 11 so as to hold the slide in extended position by reason of the pin being engaged with the adjacent end of the box or housing as shown in Figure 2.

The parts are now moved to an angle of approximately 45 degrees to release the ears 7 from the lips 5, whereupon the parts may be completely disengaged by moving the ears 7 through the open bottom of the box adjacent to lips 5. To connect the parts, the slide is extended and held by the pin whereupon the ears 7 are engaged with the lips 5 at a 45 degree angle followed by movement of the parts to normal position.

The invention is susceptible to all uses which ornamental or other chains of this type are adapted for, including wrist watch bracelets, necklaces, wrist circlets, etc.

Having thus described my invention, what I claim as new and desire to secure by Letters Patent is:—

1. In an expandible link bracelet, links including a box, a substantially L-shaped slide in the box having a pair of ears at each end thereof extending outwardly from its sides, L-shaped lips at one end of the box for engagement with the ears at the outer end of the adjacent slide, said slide having a pin-hole between its ends, a coil spring on the slide engaged at one end with the right angular end of the slide, and a back secured to the box and disposed over the spring and having an end thereof engaged with the other end of the spring.

2. In an expandible link bracelet, links including a box, a substantially L-shaped slide in the box having a pair of ears at one end thereof, L-shaped lips in the box for engagement with the ears of an adjacent slide,

said slide having a pin-hole between its ends, and a coil spring on the slide engaged at one end with the right angular end of the slide and at its other end with the adjacent end of the box.

3. In an expandible link bracelet, links including a box, a spring tensioned slide in the box having a part extending through an end of the box, connecting means on said part, and means carried by the box for removable engagement with the connecting means of an adjacent slide, said part of the slide having a pin-receiving hole which upon outward movement of the slide is exposed to receive a pin thereby to hold the slide in outward position.

4. In an expandible link bracelet, links including a box, a spring tensioned slide in the box having a part extending through an end of the box, ears on the end of said part of the slide engageable with the adjacent end of an adjacent box, and hook-shaped lips carried by the other end of the box for engagement with the adjacent ears of an

adjacent slide, said other end of the box having an opening to permit the ears of the slide to be moved therethrough in connecting and disconnecting the slide from an adjacent box.

5. In an expandible link bracelet, links including a box, a spring tensioned slide in the box having a part extending through an end of the box, connecting means on said part, and means carried by the box for removable engagement with the connecting means of an adjacent slide, said part of the slide having means which upon outward movement of the slide is exposed whereby to permit the slide to be held in its said outward position.

In testimony whereof I have signed my name to this specification in the presence of two subscribing witnesses.

CHARLES A. MEALY.
